Perry Prettyman, of George Town, ^{Deput'y in his Bedstead of Mar 31. 1834}
Delaware
Letters Patent

The Schedule referred to in in. their Letters Patent and making part of the same, containing a description in the words of the said Perry Prettyman himself of his improvement on his Bedstead patented March 31. 1834.

To all to whom these presents shall come. Be it known that I Perry Prettyman of George Town in the County of Sussex and State of Delaware have invented a new and useful improvement in bedsteads, and that the following is a full and exact description of the construction and operation of the said improvement as invented by me: My improvement consists in the manner of fastening or confining the rails by a catch and pin instead of screws or traps. After having constructed the bedstead (whether high, low or field post) in the ordinary way, that is with short tenons which should be one inch thick and from $\frac{1}{4}$ inch to $\frac{3}{4}$ long on the ends of the rails, having corresponding mortises in the posts. The upper side or edge of each tenon is then to be notched down about $\frac{1}{4}$ of an inch so as to permit the rail when the tenon is intended to be raised by the hand $\frac{1}{4}$ an inch or more. A shallow notch $\frac{1}{4}$ of an inch or more is also to be made in the lower edge of the tenon to allow the rails to settle down at time or wear of the bedstead may require. Next a hole is to be bored in each of the tenons of about the same size depth and direction as those made to receive the screws in common use for bedsteads, or it may if desired be made larger and deeper according to the size of the square shank of the catch which it is intended to receive and fit tight; this hole is simply a square piece of wrought or cast iron from $\frac{1}{4}$ in. to $\frac{3}{4}$ of an inch broad, $\frac{1}{2}$ inch thick or larger or smaller and about 5 inches long resembling the catch to a common thumb latch of a door; except that the shank is of even thickness and the inner shoulder instead of being square stands oblique to and from the shank about $\frac{1}{4}$ inch or $\frac{5}{8}$ of an inch long forming the bearing of the rail as will be herein after seen. The extremity of the shank of the catch which enters the rail is furnished with a hole about 3 inches from the shoulder of the catch for securing the catch by the passing of a strong wrought iron pin $\frac{1}{4}$ of an inch thick passing through it and the rail. The manner of fixing the catches in the rails is as follows; in the hole in the tenon being bored for the shank of the catch there is also a $\frac{3}{8}$ inch hole to be bored on

the outside of the rail two inches from the shoulder of the rail to the centre of the hole, to reach the hole where the shank is to be driven in the shank of the catch is now to be driven in with the catch down and within a short distance of their oblique shoulder, the hole in the shank now being seen in the hole on the outside of the rail, a boring bit starting the hole in the shank is to be passed through the shank and through the rail, the large hole first made on the outside of the rail is then to be firmly closed by a solid wooden pin and a hole bored through it with the bit last used from the outside side of the rail, after which the iron pin is driven through from the outside of the rail and the catch is secured; there may be other methods used to bore these holes but that here described will enable expert workmen to perform the operation quickly and correctly. The mortises of the posts are made three inches $4\frac{3}{4}$ long and gaged $7/8$ of an inch from the outside of the post, and one inch wide, the mortise is cut $3/4$ of an inch deep the part that is inch wide, then in the center of the inch mortise is to be a half inch mortise or larger if required cut so as to receive the head of the catch nearly one inch deep, next there is to be a $3/8$ inch hole bored from the inside of the post across the mortise, within a quarter of an inch of the outside of the post one inch from the edge of the post to the centre of the hole and one inch and $3/16$ from the bottom or lower edge of mid mortise, then there is to be a $3/8$ round wrought iron pin from two to two $1/8$ inches long or longer if required which is simply a piece of $3/8$ chain rod cut off to be driven in the hole across the mortise to within about a $1/8$ of an inch of the outside of the post, then a wooden pin is to be driven in the hole on the iron pin to prevent it from moving and this makes a firm fastening for the catch when the train is put in the mortise; for large high post bedsteads the best method is to put in two catches in the side rails, one even with the top edge of the tenon and the other near the bottom edge of the tenon; that is let the point of the catch come even with the bottom edge of the tenon, and put two iron pins across the mortises instead of one; one is amply sufficient for low posts and full posts; but it is best to have two for high posts; but one will do very well to put two pins across the mortises, they are to be put the same distance from the inside of the post as before described and one is to be put in $1/8$ inch from the lower edge of the mortise to the centre of the hole, and the other is to be put in one inch and $1/8$ from the top edge of the mortise to the centre of the hole, the wood behind the pin being sufficiently removed before the pin is driven in, to permit the catch to enter over the pin and take hold and to allow a

small space below the point of the catch for the further depression of the catch by wear and use, and the projection of the shoulder of the catch beyond the tenon, must be such that when the shoulder of the nail is close up or home to the post between the middle, and the point of the oblique shoulder of the catch bears on the inside of the pin; by this arrangement the shoulders of the rails are drawn into close connection with their respective posts & with a force proportionable to the incumbent weight - -

To put this bridle up it is only necessary to enter the tenons high as the mortise will admit, in which position the catch will pass over the pin in the bottom of the mortise and by then letting the nail down the oblique side of the catch takes hold on the inside of the pin and the work is done. By reversing the operation it may be taken down with equal facility and dispatch both operations being performed by the hands without tools -

Now what I claim as my invention and for which I ask Letters Patent is the pin, across the mortises, of the posts and the pin through the rails, and catches - In testimony that the foregoing is a true specification of my said invention and improvement I have hereunto subscribed my name this fourteenth day of September 1835.
